UNITED STATES PATENT OFFICE

1,998,941

ELECTRIC CIRCUIT BREAKER

Jules Perino, Philadelphia, Pa., assignor to General Electric Company, a corporation of New York

Application December 22, 1933, Serial No. 703,570

4 Claims. (Cl. 200—150)

My invention relates to electric circuit breakers, more particularly to electric circuit breakers of the so-called oil-blast explosion-chamber type wherein an initial pressure generating arc is formed for causing the circuit-interrupting oil blast, and has for its principal object the provision of simplified and improved contact structure for circuit breakers of the aforesaid type.

My invention will be more fully set forth in the following description referring to the accompanying drawing, and the features of novelty which characterize my invention will be pointed out with particularity in the claims annexed to and forming a part of this specification.

Referring more particularly to the drawing, the single figure thereof is an elevational view in cross section of one pole of a circuit breaker of the oil-blast explosion-chamber type embodying the present invention.

The explosion chamber contact structure illustrated constitutes one pole of a circuit breaker of a well-known type wherein two similar explosion chamber contact structures, comprising the two poles of the switch, are immersed in an insulating liquid as oil and are interconnected in closed circuit position by a conducting bridging member which is vertically movable within the insulating liquid with respect to the explosion chamber structure. In the present instance the explosion chamber contact structure comprises a butt contact 1, an intermediate or floating contact 2 and a movable tubular contact 3 which is carried by the aforesaid bridging member. In the closed circuit position the intermediate contact 2 is in butt contact engagement with contacts 1 and 3 so as to complete the circuit between the lead-in conductor 4 and the bridging member.

The explosion chamber structure comprises an adapter 5 and a connecting member 6 to which the adapter is connected so that the lead-in conductor 4 is electrically connected to the adapter 5 and rigidly mounted with respect thereto. The adapter 5 in turn is connected to and supports a steel cylindrical member 7 comprising an explosion chamber pot. The pot 7, which is constructed to withstand high bursting pressures, is connected at its upper inner edge to the adapter as by screw-threaded engagement indicated at 8 and at its lower edge is provided with an inwardly extending annular flange 9 forming generally the throat or exhaust of the explosion chamber through which the movable tubular contact 3 is operated.

The explosion chamber pot 7 is suitably insulated with respect to the intermediate and mov-

able contacts 2 and 3 as by inner insulating cylinders 10 and 11 fitted to the inner wall of the pot 7 and by an insulating throat bushing 12 having a central flared opening 13 for receiving the movable contact 3. The insulating cylinders 10 and 11 serve to mount and position an insulating disk 14 on which the intermediate contact 2 is mounted. The insulating disk 14 is provided with apertures 14' extending through the same and interconnecting upper and lower portions of the explosion chamber for a purpose presently described. The intermediate contact 2 is positioned in a centrally disposed aperture 15 in the insulating disk.

The throat bushing 12 is secured in position by 15 a spacing nut 16 and lock nut 17 which are threaded directly on the insulating bushing. The insulating cylinder 11 extends as at 11' over the inner edge of the explosion pot throat flange 9 and a suitable gasket 18 is positioned between the 20 overhanging flange of the throat bushing 12 and the insulation 11. The exterior of the pot 7 is suitably insulated as by a sleeve-like insulating cylinder 19 supported by an insulating flange 20 which is in turn secured to the pot 7 by a nut 21. 25

The upper butt contact 1 comprises a cylindrical guide portion 22 which is slidably mounted on a bolt 23 secured to the adapter 5 and resiliently biased, as by coil spring 24, towards the lower position illustrated. The guide bolt 23 is 30 provided with an insulating sleeve 25 and downward movement of the butt contact 1 is limited by a shoulder 22' of the guide portion 22 which is arranged to abut the corresponding shoulder 23' at the lower end of the bolt 23. The actual 35 contact making and arcing surface of the butt contact 1 is formed by a replaceable cap 26 secured as by screw-threaded engagement at 27 to the portion 22 and composed of a suitable conducting and arc-resisting metal. The electrical 40 connection between the butt contact 1 and the adapter 5 is provided by a plurality of flexible conductors 28 which directly conduct current from the adapter 5 to the contact 1 thereby protecting the biasing spring 24 from overheating. 45

The intermediate contact 2 is simply and compactly arranged within the explosion chamber and, as previously described, is insulated with respect to the pot 7 by the insulating disk 14 which likewise serves as a support for the intermediate contact. The intermediate contact comprises a short tubular member 29 of conducting material having connected thereto at opposite ends butt contact portions 30 and 31 for coacting with the contacts 1 and 3, respectively. The 55

butt contact portions 30 and 31 are conveniently formed by disk-like portions having threaded extensions or studs 30' and 31' respectively arranged to engage corresponding threaded portions in the interior of the tube 29 as illustrated. When so secured in position, the contact portions are locked with respect to tube 29 by pins 32.

- A coil spring 33 seated at one end in a recess 34 in the insulating disk 14 and at its other end 10 in a retainer 35 normally biases the intermediate contact to the lower position illustrated where it is held against further movement by the engagement of the contact portion 30 with the insulating disk 14. An insulating sleeve 36 secured to 15 the disk 14 surrounds and protects the spring 33. As in the previous instance, the contact portions 30 and 31, and likewise the removable contact tip 3' of the tubular contact, are composed of suitable arc-resisting contact metal.
- 20 Referring more particularly to the operation of the device, the closing of the circuit is effected by elevation of the tubular contact 3 which first engages contact portion 31 of the intermediate contact and elevates the intermediate contact 25 against the bias of spring 33 into engagement with butt contact 1. Overtravel of the bridging member is provided for by reason of the resiliently mounted butt contact 1.

Opening of the circuit is effected by lowering 30 of the tubular contact 3, the contacts continuing in following engagement until the butt contact 1 reaches its lower limit of travel, at which time separation of the butt contact and intermediate contact 2 occurs. The resulting arc within 35 the explosion chamber, which is filled with oil or other suitable insulating liquid, generates a high pressure within the chamber by reason of decomposition of some of the insulating liquid by the arc. Continued lowering of the contact 3 results in separation of the same from the intermediate contact when the latter contact reaches its lower limit of travel, resulting in a second arc 40 in series with the first or pressure generating arc between the contacts 2 and 3. As the tubular contact 3 passes through the throat of the explosion chamber the aforesaid pressure causes a blast of oil from the chamber through the second arc and into the tubular contact to exhaust exteriorly of the explosion chamber thereby 45 extinguishing said arc and interrupting the circuit.

After circuit interruption the explosion chamber refills with oil from the main circuit breaker tank, the adapter 5, which forms the top wall of 50 the explosion chamber, being provided with an aperture 37 for permitting escape of accumulated gas and serving to limit excessive pressure. The accumulation of gas generated within the explosion chamber is localized to a considerable extent at the upper part of the explosion chamber by reason of the insulating disk 14, the apertures 14' serving generally to transmit pressure to the lower part of the chamber so that a blast 55 of oil rather than gas is obtained for interruption of the arc.

It should be understood that my invention is

not limited to specific details of construction and arrangement thereof herein illustrated, and that changes and modifications may occur to one skilled in the art without departing from the spirit of my invention.

5

What I claim as new and desire to secure by Letters Patent of the United States is:

1. An electric circuit breaker of the oil-blast explosion-chamber type comprising relatively movable contacts including an intermediate contact, said intermediate contact comprising a tubular conducting member, insulating structure in which said tubular member is slidably mounted, and butt contact arcing portions detachably connected to the opposite ends of said tubular member. 10

15 2. An electric circuit breaker of the oil-blast explosion-chamber type comprising relatively movable contacts including an intermediate contact, said intermediate contact comprising a tubular conducting member, and disk-like butt contact portions at opposite ends of said tubular member having screw-threaded stud portions extending into and engaging said tubular member for electrically and mechanically connecting said 20 butt contact portions thereto.

25 3. An electric circuit breaker of the oil-blast explosion-chamber type comprising relatively movable contacts including an intermediate contact, means forming an explosion chamber in which said contacts coat, an insulating disk mounted in said chamber and supporting said intermediate contact, said intermediate contact comprising a cylindrical conducting member slidably mounted in said insulating disk and disk-like butt contact portions secured and electrically connected to opposite ends of said cylindrical member, and means biasing said cylindrical member in a direction longitudinally thereof, one of 30 said disk-like butt contact portions coacting with 35 said insulating disk for limiting movement of said intermediate contact.

4. An electric circuit breaker of the oil-blast explosion-chamber type comprising relatively movable contacts including an intermediate contact, means forming an explosion chamber in which said contacts coat, an insulating disk disposed within said chamber and dividing the same into upper and lower portions, said insulating disk having apertures therein including an aperture for receiving said intermediate contact, said intermediate contact comprising a cylindrical conducting member slidably mounted in said last-named aperture, disk-like butt contact portions secured and electrically connected to the opposite 55 ends of said cylindrical member, a spring interposed between said insulating disk and one of said butt contact portions for biasing said intermediate contact in a direction longitudinally thereof, the other of said butt contact portions engaging 60 said insulating disk for limiting movement of said intermediate contact, and an insulating sleeve depending from said insulating disk and surrounding said spring. 50
